UNITED STATES PATENT OFFICE.

FREDERICK P. LAMPHARE, OF PRAIRIE DU CHIEN, WISCONSIN.

DESIGN FOR A RACK.

44,372.

Specification for Design.

Patented July 22, 1913.

Application filed April 19, 1913. Serial No. 762,413. Term of patent 3½ years.

To all whom it may concern:

Be it known that I, FREDERICK P. LAMPHARE, a citizen of the United States, residing at Prairie du Chien, in the county of Crawford and State of Wisconsin, have invented a new, original, and ornamental Design for Racks, of which the following is a specification, reference being had to the accompanying drawing, forming part thereof.

The figure is a perspective view of the rack showing my design.

I claim:

The ornamental design for a rack as shown.

FREDERICK P. LAMPHARE.

Witnesses:

JOHN C. BUNDERS,
ELMER STEINER.
